UNITED STATES PATENT OFFICE.

WALTER LARKIN, OF PHILADELPHIA, PENNSYLVANIA, ASSIGNOR TO H. BRINTON COMPANY, OF PHILADELPHIA, PENNSYLVANIA, A CORPORATION OF PENNSYLVANIA.

YARN-CHANGER.

1,359,258.

Specification of Letters Patent. Patented Nov. 16, 1920.

Application filed December 27, 1916. Serial No. 139,120.

To all whom it may concern:

Be it known that I, WALTER LARKIN, a citizen of the United States, residing in Philadelphia, Pennsylvania, have invented 5
5 Yarn-Changers, of which the following is a specification.

One object of my invention is to provide a compact and positive thread or yarn changing mechanism, especially adapted for 10 use on Dogless and French welt knitting machines, whereby it shall be possible to alter the color or weight of the thread delivered to the needles without the formation of long ends at the points of junction of the different threads and the consequent necessity, 15 in the case of striping machines, for the subsequent removal of such ends which would otherwise mar the face of the fabric.

Another object of the invention is to so 20 guide the thread at the time of change, that it leads away from the needles in such a direction as to prevent the possibility of its being licked into them and kept out of the shears;—the thread feeding fingers being so 25 placed as to impart considerable tension to that portion of the thread extending from the active finger, through the shears and across the needles.

It is further desired to provide a thread 30 or yarn changer which shall include means for positively moving the thread feeding fingers in both directions;—the arrangement being such as to insure leading the thread into the shears and withdrawing it from the 35 needles at definite times.

I also desire to provide a novel means for supporting the thread feeding fingers and shears in definite relation to the needles of a knitting machine, with a view to obtaining 40 the above noted objects and especially for the purpose of eliminating the long loose knitted-in ends of the thread which ordinarily occur at the points of change.

Another object of the invention is to provide 45 a striping machine with an attachment whereby it shall be possible to utilize it for making French welts.

These objects and other advantageous ends I secure as hereinafter set forth, reference being had to the accompanying drawings, in which,

Figure 1 is an elevation of a portion of a circular knitting machine illustrating my invention as applied thereto;

Fig. 2 is a plan of the structure shown in 55 Fig. 1;

Fig. 3 is a plan of my thread changing mechanism taken at right angles to the plane of movement of the thread-feeding fingers;

Figs. 4 and 5 are sections on the lines 4—4 60 and 5—5, Fig. 3, illustrating the detail construction of certain parts of the device;

Fig. 6 is a detached perspective of the shears;

Fig. 7 is a fragmentary section illustrating the arrangement of the shear blades;

Figs. 8 and 9 are fragmentary plans, to some extent diagrammatic, illustrating the operation of my invention;

Fig. 10 is a section plan view on the line 70 10—10, Fig. 1; and

Fig. 11 is a perspective of certain of the parts shown in Fig. 10.

In the above drawings, 1 represents the stationary supporting plate or base of a circular knitting machine having a rotary cam ring 2 from which a pair of standards 3 project upwardly for the support of a cross bar 4 carrying a dial post 5. This latter carries a dial with its associated needles, and these latter are actuated by suitable cams supported by a cam plate 6.

Mounted on the upper edge of the cam ring 2 so as to project substantially parallel with its axis of rotation, are two posts 7 supporting a casting 8 which includes a lug 9 having flat top and bottom faces lying in a plane at about 30° to the horizontal. Extending through this lug in a line perpendicular to its inclined faces is a bolt or stud 10 having rotatably mounted on it a pair of thread guides or fingers 11 and 12, for which purpose the top of the lug is transversely slotted for the reception of a flat plate 13. This carries an arm 14 and a sleeve 15, of which the latter forms a journal for the lower finger 12.

Also mounted on the bolt 10 above the sleeve 15 is a second washer 16, a sleeve 17 on which the thread guide 11 is carried, and 100 a washer 18; this latter being engaged by a nut 19 threaded on the bolt whereby said

- 5 sleeves and washers are rigidly clamped together while the two guides 11 and 12, being of slightly less thickness than the sleeves, are left free to turn on the latter. Each of said thread guides has two notches 20 and 21 on one edge, of which those of the upper guide 11 are placed to be engaged by a spring-pressed dog 22, while those of the second or lower finger 12 are likewise positioned so that either of them may be entered by a second spring-pressed dog 23;—the arrangement being such that in both cases the fingers tend to remain in either of two positions.
- 10 15 The dogs 22 and 23, as shown in Figs. 2 and 4, are slidably mounted in a block 24 carried by the arm 14 and the thread guides are so proportioned and mounted that their thread guiding ends or eyelets are immediately adjacent the cylindrical surface defined by the outer edges of the needles, when said guides are held in their inner or active positions by reason of the engagement of the dogs 22 or 23 with the inner one of their 25 notches. When the second or outer of the notches is engaged by its dog, the guide is held thereby with its feeding end away from and elevated relatively to its former position adjacent the needle cylinder.
- 20 25 30 Each of the thread guides is of substantially L-shaped form and as shown in Fig. 3, is pivotally supported about the middle of its shorter arm, which in the case of the guide 11 has a projecting lug 25, while the same arm of the second guide 12 has a similar lug 26. In addition the thread guide 11 adjacent the point of junction of its arms has an outwardly projecting lug 27 at which point the thread guide 12 likewise has a 35 40 similar lug 28.
- For actuating the thread guides at predetermined times I mount on the fixed plate 1 a tubular guiding standard 29, in which is vertically slidable a rod 30 having fixed 45 to its upper end a plate 33. On the top surface of the plate is bolted a cam plate 34 having an active edge 32 placed at such distance from the vertical center line of the needle cylinder that when raised to the 50 proper levels, it is capable of engaging either of the lugs 25 or 26 of the thread guides to swing the inner ends of the latter from their outer positions into positions immediately adjacent the cylinder needles.
- 55 60 65 This plate 34 has an extension 34^a having an active edge 35 so placed as to coat with a shear operating arm 48 hereafter described. A second vertically slidable rod 31 is guided in the base plate 1 and in a projecting portion 36 of the standard 29, having its upper end fixed to the plate 33. An arm 37 is pivoted on this rod 31 and while at one end it carries a pair of rollers 38 and 39, its second end is clamped in any adjusted 70 75 80 85 90 95 100 105 110 115 120 125 130 position by a bolt 40 which passes through

a slot 41 formed in the plate 33 concentric with said rod;—it being thus possible to adjust said arm 37 on the rod to vary the distance of the rollers from the vertical center line of the needle cylinder and afterward to retain said arm in any adjusted position.

The two rollers 38 and 39 are so placed as to be capable of respectively coöoperating with the lugs 27 and 28 of the thread guides to swing them on their supporting structure to withdraw their thread delivering ends from positions adjacent the needle cylinder. Normally the rods 30 and 31 support the cam plate 32 and rollers 38 and 39 at such levels that they cannot engage the lugs on the yarn guides as the latter are rotated with the cam cylinder 2, but by any suitable means forming no part of the present invention, they may be periodically raised so as to bring said cam plate 32 to either of two levels, on one of which it will engage the lug 25 and in the other, the lug 26. The rollers 38 and 39 are so placed that when the plate 32 engages the lug 25 for example, the roller 39 will engage the lug 28, and when said plate is placed to engage the lug 26, the roller 38 will engage the lug 27.

The supporting structure 8 in addition to the above described thread guides or fingers and their associated parts, likewise carries an arm 42 which projects toward the needle cylinder and at its inner end has rotatably mounted in it a pivot spindle 44 on whose lower end is fixed a scissors or shear blade 43. Said arm 42 is so mounted that the pivot pin 44 extends substantially parallel to the bolt or stud 10 on which the thread guides are mounted so that the shear blade 43 is movable in a plane substantially parallel to said guides.

Likewise mounted on the pin or post 44 in engagement with the blade 43 is a second shear blade 45 which however is held from movement by reason of its being provided with two projecting lugs 46 which extend on either side of the arm 42. Immediately above and in contact with the second shear blade 45 is a third or holding blade 47 somewhat similar in form to the shear blade 43 and caused to move with the same upon the post 44 by means of a cam actuated bar 48 whose inner end is turned up as indicated at 49 so as to pivotally enter two holes 50 and 51 in the adjacent ends of the blades 43 and 47.

The outer end of this bar extends through and is guided by a plate 52 bolted to the outer end of the arm 42 and is normally held in its outer position with the shear blades closed by a spring 53 which extends between its inner end 49 and the plate 52. The post 44 on which the shear blades are mounted extends through the inner end of the arm 42 and has on its upper end a washer

54, between which and the adjacent portion of said arm is mounted a spring 55 whereby the shear blades are at all times drawn together.

5 It is to be particularly noted that while the thread guides are placed to lie in advance of the descending portion of the needle wave so that when they are delivering thread they are slightly below the hooks of the needles, 10 the shears are above and project over the needles after they have been lowered, as shown in Fig. 2.

Under operating conditions if it be assumed that one color of thread is being delivered to the cylinder needles by the lower thread guide 12, thread of a second color then extends through the upper thread guide 11 and thence to the shears, where its end is frictionally held between the blade 20 47 and the upper shear blade 45;—the shears being closed, (Fig. 3).

After a predetermined number of rows has been knit from the thread delivered by the guide 12, suitable controlling mechanism acts on the rod 31 to elevate the structures carried thereby to such a position that the cam plate 32 is brought into a plane including the projecting lug 25 of the thread guide 11, and a subsequent engagement of 30 said lug with the plate 32 swings this guide on its pivot so as to bring its thread delivering end into a position immediately adjacent the needles.

Owing to the position of the shears as well as to that of the extremity of this guide, Fig. 8, the second thread is thus moved directly across the descending edge of the needle wave at such an angle and in such a position that it is necessarily and 40 certainly engaged by one of the needles and at once is knitted into the fabric sufficiently to be held in place. Immediately thereafter the continued revolution of the cam cylinder brings the projecting end of the arm 48 45 into engagement with the cam plate 34, forcing it in so as to open the shears and thus release the end of the second thread.

At or about the time of opening of the shears the lower one of the rollers 39 comes 50 into engagement with the projecting lug 28 of the lower thread guide 12, swinging its thread delivering end outwardly and positively withdrawing the thread served by it from the needles. Owing to the position 55 of the shears whose blades are now open, (Fig. 9) and to the direction in which this first strand of thread runs from the needles, it is at once carried between the open shear blades which are timed to immediately shut by reason of the disengagement 60 of the arm 48 from the main part of the cam plate 34. Such closing of the shears not only cuts the first thread but leaves one end thereof frictionally held between the

upper shear blade 45 and the plate 47, while 65 its other end is knitted into the fabric. Possible damage to the shear blades is prevented by the auxiliary cam plate 34a whose active edge 35 lies farther away from the cylinder than the edge 32 and receives the 70 end of the bar 48 after this has been disengaged by the cam 34.

From the above description it will be obvious that not only is the second thread so 75 knitted into the fabric that it leaves practically no projecting end, but the first strand is cut off by the shears so close to the needles that the amount of overlap of the two threads is a minimum and it is practically certain that the ends shall not be visible. 80 Obviously this desirable object is due to the fact that the thread guides and shear are arranged as specified, at an acute angle to the horizontal which makes possible the peculiar placing of these elements relatively 85 to the knitting wave of the needles.

When it is desired to utilize a machine equipped with the invention above described for French welt work, I mount in the cam cylinder 2 a vertically extending spindle 60 90 having fixed to its upper end an arm 61 which projects horizontally adjacent the arm 25 of the thread guide 11 for example. This spindle has mounted on it a coiled spring 62, having its ends respectively fixed 95 to the cam cylinder 2 and to said spindle in such manner as to at all times tend to cause the arm 61 to engage and act upon the arm 25 so as to swing the thread guide away from the needle cylinder and the lower end 100 of the spindle has fixed to it in any suitable manner, a lever 63 of which one arm projects outwardly a short distance above the surface of the structure 1 in position to be engaged by a cam arm 64 carried by said 105 structure when it has been brought by suitable mechanism to the proper level.

Between this lever 63 and the top surface of the structure 1 is pivotally mounted a latch 65 at all times pressed toward said 110 lever 63 by a suitable spring 66 and mounted under the latter in position to be also engaged by said cam arm under certain conditions. The outer end of said latch has the form of a hook whereby the lever 63 115 may be held in a retracted position with the spindle 60 and arm 61 held against the action of the spring 62 in such position that said arm is immediately adjacent but practically inoperative upon the thread guide 11 120 when this is in its thread delivering position. The second arm of the lever 63 is so placed that after the latch 65 has been swung on its pivot to release this lever, it is retained in a retracted position until the 125 lever has been moved by the cam arm 64 into engagement with the hook of said latch.

As shown in Fig. 10, when the latch is in such position that its hook holds the lever 63, its outer extremity projects sufficiently to be engaged by the cam arm 64 when the latter is brought to the level of the top of the structure 1.

In order to equip the machine for French welt work, it is necessary, in addition to the arm 61 with its associated parts, to provide 10 a second thread feeding attachment, which as shown in Fig. 2, may be an absolute duplicate of that above described except that it does not include said arm and its actuating mechanism. Without further describing 15 this duplicate attachment, it is sufficient to note that its two thread guides 11^a and 12^a with the adjacent shears and their actuating and controlling members are operated by the cam elements 32 and 38 in the same 20 manner as and immediately after the actuation of the thread guides and shares 11, 12, etc., as previously described.

With such an arrangement of parts, striped goods may be made as before al- 25 though in this case there are two thread feeds instead of one in operation at any given time, and when French welt work is to be made, the cylinder needles adjacent the thread guides 11 and 12 are raised to 30 the tuck point by suitable mechanism, so that they are prevented from casting off their stitches or loops and the dial needles adjacent the thread guides 11^a and 12^a are placed by other suitable mechanism, at the 35 welt point. The cam arm 64 is likewise so operated as to be brought into engagement with the latch 65, thus causing freeing the lever 63 from the latch 65 and permitting the spindle 60 to turn under the action 40 of the spring 62 into a position in which the arm 61 engages the thread guide arm 25. The thread guide 11 is therefore moved a short distance away from the cylinder needles, which however is sufficient to prevent 45 the thread being delivered to said needles while still allowing it to be fed to the dial needles.

As a consequence of the above described arrangement, the dial needles knit one part 50 of the welt while the cylinder needles adjacent the thread guides 11^a and 12^a (of which but one is delivering thread) knit the other part of the welt. A characteristic French welt is thus formed and after a de- 55 sired length has been knitted, the cam arm 64 is raised to such a position as to engage the projecting arm of the lever 63, thus swinging it inwardly until it is engaged and held by the hooked end of the latch 65. At 60 the same time the spindle 60 and arm 61 are turned sufficiently to permit the thread guide 11 to return to a position in which thread is delivered to the adjacent cylinder needles.

65 In order that this action shall be possible,

it is to be understood that the arm 61 is so mounted that while it moves the thread delivering end of the guide 11 far enough away from the cylinder needles to prevent them receiving said thread, the spring pressed dog 22 merely rides up on the side of the inner notch in said thread guide without being caused to pass over into the outer notch. Consequently said thread guide is free to return to its thread delivering position under the action of said dog 22.

At the same time that the thread guide 11 is permitted to move into its thread delivering position, the adjacent cylinder needles are likewise permitted to rise to their knitting positions, while at the opposite side of the machine the dial needles are also permitted to move from the welt point to positions in which they knit.

By utilizing the above described method and apparatus for the formation of French welts, I obviate what I have found to be the objectionable possibility of the thread being cut by the latches of certain of the dial needles as said latches are moved to their closed positions. With my apparatus arranged and operated as described, the cylinder needles, being held at the tuck point, definitely position the thread on the adjacent dial needles during the knitting of the welt, so that the latches of these latter needles operate in the proper manner without possibility of injury to said thread. When the welt is made in the ordinary manner the thread is free to assume any of a number of positions on the dial needles, since so far as I am aware, it has not hitherto been definitely positioned and when the latches of said needles are closed, they pinch and frequently actually cut the thread in case it does not move upon the needles with the utmost freedom.

By mounting the yarn fingers with their axis of oscillation inclined to the center line of the cylinder as described, I am enabled to so mount the shears that the distance from the point at which they engage a thread to the eye of the finger is materially shorter than would be the case if said needles oscillated on an axis in one case at right angles to the center line of the cylinder or on an axis parallel with said center line. Moreover it makes possible the utilization of yarn finger structures of simple and inexpensive construction since they are made of flat material and have their cam actuated lugs both extending in the plane of the body portion.

I claim—

1. The combination with the cylinder and needles of a circular knitting machine, of a thread guide mounted to move in a plane inclined to the center line of said cylinder; with means for moving said guide positively both into and out of a position in which it

delivers thread to the needles; and shears mounted to cooperate with the thread guide in holding the thread, under predetermined conditions, in a line extending across the path of the needles.

2. The combination with the cylinder and needles of a circular knitting machine of a pivot structure mounted to extend in a line inclined to the center line of the cylinder; 10 a lever mounted on said structure and having a thread delivering opening; and means for turning said lever on the pivot structure in a plane substantially parallel with the descending edge of the needle wave to bring 15 its opening into and out of a position radially adjacent said wave edge.

3. The combination with the cylinder and needles of a circular knitting machine of a plurality of thread guides mounted to swing 20 in planes substantially parallel with the descending edge of the needle wave; with means for moving said guides into and out of positions with their thread delivering portions in radial alinement with said wave 25 edge.

4. The combination with the cylinder and needles of a circular knitting machine of a plurality of thread guides mounted to swing in planes inclined to the center line of said 30 cylinder; means for positively moving said guides into and out of positions in which thread is delivered to the needles; and means for temporarily holding the ends of the threads within the circle of the needles at 35 predetermined times in the operation of the machine.

5. The combination with the cylinder and needles of a circular knitting machine of a plurality of thread guides mounted to swing 40 in planes substantially parallel with the descending edge of the needle wave and each having two actuating lugs; means for alternately engaging the lugs of each guide to alternately move the latter into a position 45 in radial alinement with said wave edge; and means for severing the thread from each guide when it has been moved to its outer position.

6. The combination with the cylinder and 50 needles of a circular knitting machine of a plurality of thread guides mounted to swing in planes substantially parallel with the descending edge of the needle wave; means for alternately moving said guides into and 55 out of positions with their thread delivering portions radially adjacent said wave edge; means for severing the thread from each guide when it has been moved to its outer position; and means for holding the thread 60 after it has been severed.

7. The combination with the cylinder and needles of a circular knitting machine of a plurality of thread guides mounted to swing in planes inclined to the center line of the

cylinder and each having a plurality of 65 actuating lugs respectively projecting in parallel planes; with cam mechanism for alternately engaging said lugs of each yarn guide to move it into and out of position to deliver yarn to the needles. 70

8. The combination with the cylinder and needles of a circular knitting machine of a thread guide; means for actuating said guide to positively move its thread delivering portion both into and out of a position 75 adjacent the needles; means for severing the thread; and means for holding the end of the thread in position to lead it at an acute angle across the cylindrical surface in which the needles operate, when the guide 80 is moved to its inner position.

9. The combination in a dial knitting machine of a plurality of thread guides; a thread cutting device; means for actuating said guides to cause thread to be alternately delivered from them; means for causing the cutting device to sever a thread when it is withdrawn from the needles; and a device independent of said guide-actuating means for causing one of the guides to move 90 to a position in which it delivers thread to the dial needles without delivering it to the cylinder needles.

10. The combination in a knitting machine of two thread guides each having an 95 operating arm; a spindle having a projecting arm placed to engage the operating arm of one of said guides to move the latter in one direction; means for rotating said spindle to cause the arm to act on the thread 100 guide; and cam mechanism mounted to periodically actuate the operating arms of the two guides under predetermined conditions.

11. The combination in a knitting machine of two thread guides each having an 105 operating arm; cam means for positively actuating said arms in both directions to move the guides into and out of operative positions; and an independent member for actuating one of said guides to a less extent 110 than said cam means.

12. The combination in a knitting machine having cylinder and dial needles; thread guides; means for moving said guides into and out of positions in which thread is delivered to said needles; and an auxiliary device for moving one of said thread guides from a position in which it delivers thread to both sets of needles, to a position in which it delivers thread to the 120 dial needles only.

13. The combination in a knitting machine having cylinder and dial needles; two sets of thread guides; means for moving either guide of each set into and out of positions in which thread is delivered to said needles; and an auxiliary device for moving one of said thread guides from a po- 125

sition in which it delivers thread to both sets of needles, to a position in which it delivers thread to the dial needles only.

14. The combination in a circular knitting machine of a plurality of thread guides operative in planes inclined to the axis of the cylinder and each having two actuating lugs projecting one above the other; cam mechanism operative to move said guides alternately into and out of operative positions; with a combined shearing and thread holding device positioned to hold the thread leading from any inoperative thread guide.
15. The combination with the cylinder and needles of a circular knitting machine of a plurality of thread guides mounted to turn on an axis inclined at an acute angle to the center line of the cylinder and each having a throw-in and a throw-out projection one above the other; with a cam device automatically adjustable to engage either of the throw-in lugs and including a portion positioned to engage the throw-out lug of that guide other than the one whose throw-in lug was last engaged.
16. The combination with the cylinder and needles of a circular knitting machine of a plurality of thread guides mounted to turn on an axis inclined at an acute angle to the center line of the cylinder and each having a throw-in and a throw-out projection one above the other; with a cam device automatically adjustable to engage either of the throw-in lugs and including a portion positioned to engage the throw-out lug of that guide other than the one whose throw-in lug was last engaged, the throw-in lugs of said guides all lying above the throw-out lugs.
17. The combination with the cylinder and needles of a circular knitting machine of a plurality of thread guides mounted to turn on an axis inclined at an acute angle to the center line of the cylinder and each having a throw-in and a throw-out projection one above the other; with a cam device automatically adjustable to engage either of the throw-in lugs and including a portion positioned to engage the throw-out lug of that guide other than the one whose throw-in lug was last engaged; with a device positioned to cut and hold the thread from any guide when it is actuated by engagement of its throw-out lug with the cam device.
18. The combination with the cylinder and needles of a circular knitting machine of a plurality of thread guides pivotally mounted to turn on an axis inclined at an acute angle to the center line of the cylinder and each formed with a throw-in and a throw-out lug respectively projecting in two planes; with two cams automatically adjustable into and out of said planes respectively and mounted so that when one cam engages the throw-in lug of one guide the other cam will engage the throw-out lug of the other guide.
19. The combination with the cylinder and needles of a circular knitting machine of a plurality of thread guides mounted to turn on an axis inclined at an acute angle to the center line of the cylinder and each having a throw-in and a throw-out lug projecting one above the other; cam mechanism for alternately engaging the two lugs of each guide; with a shearing device including a blade also mounted to turn on an axis at an acute angle to the needle cylinder and positioned to cut a thread from any guide when the latter has been moved by the cam mechanism to an inactive position.
20. The combination with the cylinder and needles of a circular knitting machine of a plurality of thread guides mounted to turn on an axis inclined at an acute angle to the center line of the cylinder and each having a throw-in and a throw-out lug projecting one above the other; cam mechanism for alternately engaging the two lugs of each guide; with a shearing device including a blade also mounted to turn on an axis at an acute angle to the needle cylinder and positioned to cut a thread from any guide when the latter has been moved by the cam mechanism to an inactive position, said shearing device being adjustable to vary the relative time of its operation.
21. The combination with the cylinder and needles of a circular knitting machine of a thread guide mounted to oscillate in a plane substantially parallel with the descending edge of the needle wave and having a throw-in and a throw-out lug; cam mechanism automatically adjustable to operate on said lugs alternately to cause the guide to be moved into and out of a position in which thread is delivered to the needles.

In witness whereof I affix my signature.
WALTER LARKIN.
